[57] CLAIM

The ornamental design for a modular army service
stripe thereof, as shown and described.

DESCRIPTION

FIG. 1 is a top perspective view of a modular army
service stripe showing my new design;

FIG. 2 is a bottom perspective view;

FIG. 3 is a perspective view of a modular army service
stripe showing a second embodiment of my new design,
the opposite side being the same;

FIG. 4 is a perspective view of a modular army service
stripe showing a third embodiment of my new design,
the opposite side being the same; and

FIG. 5 is a perspective view of a modular army service
stripe showing a fourth embodiment of my new design,
the opposite side being the same.

FIG. 1

FIG. 2

FIG. 3

FIG. 4

FIG. 5
